HERMANN EDGAR EBBS, OF NUEREMBERG, GERMANY, ASSIGNOR TO THE FIRM OF VEREINIGTE MASCHINENFABRIK AUGSBURG AND MASCHINEN-BAUGESELLSCHAFT NUERMBERG A. G., OF NUEREMBERG, GERMANY.

WATER-COOLED VALVE.

SPECIFICATION forming part of Letters Patent No. 698,474, dated April 29, 1902.

Application filed October 25, 1901. Serial No. 79,946. (No model.)

To all whom it may concern:

Be it known that I, HERMANN EDGAR EBBS, a subject of the King of Great Britain, residing at Nuremberg, Germany, have invented 5 certain new and useful Improvements in Water-Cooled Valves, of which the following is a specification.

The present invention consists of an improved water-cooled valve and comprises the 10 details of construction hereinafter set forth, and particularly pointed out in the claims.

In order to render the present specification easily intelligible, reference is had to the accompanying drawings, in which similar letters of reference denote similar parts throughout the several views.

Figure 1 is a vertical section through a valve provided with the cooling device, and Fig. 2 is a horizontal section showing the upper wa- 20 ter-channel.

The invention may be applied to any class of valve and is particularly advantageous in connection with the outlet-valves of hydro-carbon-engines.

To the body *a* of the valve the stem *b* is screwed in the known manner by means of its flange *c*, the parts being rendered tight by means of a packing-ring *d*. Between the body *a* and the inner face of the flange *c* two 25 sets of channels *h* and *i* are arranged, through which the cooling fluid first passes from the center of the valve to the rim along the upper channel and then down the opening *k* to the outer end of the lower channel *i*, back through 30 the latter to the center of the valve, and out through the hollow stem *b*, the inner diameter of which is larger than a tube *l*, extending through the interior *n* of the said stem and through which the cooling fluid is fed to the 35 center of the upper channel *h*. The two sets of channels *h* and *i* may be formed in any desired manner; but it has been found advantageous in practice to form the upper channel of a spiral shape, as will be seen from 40 Fig. 2, leading in a set of coils from the center to the rim and being cut in the interior face of the body *a* of the valve. An intermediate plate *e*, having a smooth upper face and a channel *i* in its lower face, is then closed 45 against the ends of the ribs *f* of the upper

channel, and the flange *c* closes against the ribs *g* of the channel of the intermediate plate *e*, the outer ends of the two channels being in communication one with the other through the vertical port *k* and the center of 55 the lower spiral channel *i* being in communication with the interior of the hollow stem outside the feed-pipe *l*.

As will be readily understood from the foregoing specification, the cooling fluid passes 60 through the pipe *l* to the center of the upper spiral channel *h*, along the same, down the port *k*, and back along the lower spiral *i* and out at the stem. In its passage the cooling fluid circulates thoroughly over both faces of 65 the valve and will effectually cool the same.

I claim as my invention—

1. In a valve, the combination of a hollow body having a spiral groove therein, an intermediate plate closing said groove, said plate 70 having a similar spiral groove in its base, means for closing said similar groove, a port for establishing communication between the two spiral grooves, and means for causing a flow of cooling liquid through the said spiral 75 grooves, substantially as described.

2. In a valve the combination of a hollow body having a spiral groove therein extending from the center to the rim in a plane parallel to the valve-face, an intermediate plate 80 having a smooth face to close the said spiral groove and having a similar spiral groove in the opposite face, a hollow valve-stem having a smooth face to close the lower spiral groove and adapted to screw into the hollow valve- 85 body, the interior of the hollow stem being in communication with the center of the lower channel, a fluid-feed pipe within the said hollow stem in communication with the center of the upper spiral channel and a port to es- 90 tablish communication between the outer ends of the said upper and lower channels substantially as described and for the purpose specified.

In witness whereof I have hereunto set my 95 hand in presence of two witnesses.

HERMANN EDGAR EBBS.
